UNITED STATES PATENT OFFICE.

WILLIAM A. STEINRUCK, OF PUEBLO, COLORADO.

CAR-FAN.

SPECIFICATION forming part of Letters Patent No. 650,802, dated May 29, 1900.

Application filed May 22, 1899. Serial No. 717,680. (No model.)

To all whom it may concern:

Be it known that I, WILLIAM A. STEINRUCK, a citizen of the United States of America, residing at Pueblo, in the county of Pueblo and State of Colorado, have invented certain new and useful Improvements in Car-Fans; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in cooling and ventilating fans specially adapted for use on railway-cars and other rapidly-moving vehicles.

20 My improved fan mechanism is automatic in operation, the impelling power being the air-current induced or created by the movement of the train. Briefly stated, the mechanism comprises a wheel located outside the car and adapted to be actuated by a current 25 of air, a fan-wheel located inside the car, and a suitable connection between the exterior wind-wheel and the interior fan-wheel whereby the latter is operated by the rotation of the former.

30 The invention embraces a construction whereby any desired number of fan-wheels may be operated from the same wind-wheel, also speed-reducing means whereby the fan-wheels may be rotated slower than the wind-wheel, and means for controlling the current within the car by the regulation or adjustment of the arms of the fan wheel or wheels.

35 The invention will now be described in detail, reference being made to the accompanying drawings, in which is illustrated an embodiment thereof.

In the drawings, Figure 1 is a vertical longitudinal section taken through the top of 40 a passenger-car equipped with my improvement. Fig. 2 is a top view of the fan-wheel, shown on a larger scale. Fig. 3 is a sectional elevation taken through the same. Fig. 4 is a side elevation of the fan-wheel-operating 45 mechanism, shown on a larger scale than in Fig. 1. Fig. 5 is a horizontal section taken through the wind-wheel casing. Fig. 6 is a

section taken on the line X X, Fig. 5. Fig. 7 is a perspective view of the locking-dog employed in connection with my improvement. 55

Similar reference characters indicating corresponding parts in the views, let the numeral 5 designate a casing having funnel-shaped open extremities. In this casing is journaled a vertical shaft 6, upon which is made fast a 60 horizontal wind-wheel 7, located within the casing and adapted to be operated by a current of air entering the casing in either direction or through either of the funnel-shaped casing extremities. This wheel is substantially of the same construction as the Pelton water-wheel and need not be described more in detail. The wind or air-current enters the pockets of the wheel at one extremity and escapes from the said pockets at the other extremity of the casing, which is so constructed 65 as to direct the air-current into the pockets of the wind-wheel in the most advantageous manner. The shaft 6 projects both above and below the casing, its extremities being 70 journaled in ball-bearings 8. Between the ball-cup of the lower bearing and the bottom of the casing is located a gear 9, fast on the shaft 6 and meshing with a larger gear 10, fast on a depending shaft 12, passing through 75 a bracket 13, made fast to the top 14 of the car. The shaft 12 passes through the top of the car and through a sleeve 15, which is formed integral with the bracket 13, projecting inside the car. The lower portion of this 80 sleeve is enlarged to form a ball-cup 16, in which are located a number of sets of balls arranged one above another and separated by washers or flat metal rings. The upper portion of the shaft 12 engages a similar ball-bearing 17, located between the gear 10 and the top of the bracket 13. The gears 9 and 85 10 are inclosed by a housing cast integral with the bottom of the casing.

Below the ball-cup 16 a hub or enlargement 90 12^a is formed on the shaft 12. In this hub are journaled the inner extremities of a number of spindles 19. The outer portions of these spindles are journaled in bearings 20^a, formed in the rim of a saucer-shaped plate 100 20, mounted on the lower extremity of the shaft 12 and arranged to turn therewith. Beneath the plate 20 a nut 21 is screwed on the said shaft. A bevel-pinion 22 is made fast

to each spindle 19 at a suitable point between the spindle-bearings. These pinions mesh with a gear 23, loosely mounted on the shaft 12 between the plate 20 and the hub 12^a of the shaft. To the extremities of the spindles, which project beyond the bearings 20^a, are attached the fan-blades 24. By means of this construction it is evident that all the fan-blades may be simultaneously adjusted to keep the same position. By turning any blade the pinion 22 is turned and the gear 23 actuated, imparting a corresponding movement to all the pinions 22, and consequently to all the fan-blades.

15 In order to operate a number of fans in the same car, the shaft 12 is provided with a bevel-pinion 25, which meshes with a similar pinion 26, made fast to one extremity of a horizontal shaft 27, which may be provided 20 with other pinions 28, only one being shown. Each pinion 28 meshes with a pinion 29, made fast to the top of a fan-operating shaft 12, surrounded by a sleeve 15, the construction below the pinion 29 being the same as shown 25 in Fig. 3 of the drawings.

When the fans 24 are properly adjusted, they are locked in the desired position by means of a vertically-movable gravity-dog 30, mounted on a pin 31, engaging a socket 32, formed in the plate 20. The dog is adapted to engage the gear 23 and is provided with teeth to interlock with the cogs of the gear. When it is desired to adjust the fan-blades, the dog 30 is lifted from engagement with the 35 cogs of the gear and turned to the dotted-line position in Fig. 3. It is evident that when the blades are in the horizontal position shown in Fig. 3 their rotation imparts little or no agitation to the atmosphere. By inclining these blades in one direction a downwardly-directed air-current will be induced as the fan-blades rotate, while when they are inclined in the opposite direction an upwardly-directed current would result. The 40 motion of the fan-blades may be controlled or entirely stopped, if desired, by means of a cut-off valve 33, mounted on journals 34, engaging sockets formed in the casing on each side of one of its funnel-shaped mouths. 45 If this valve is open wide, the air-current enters the casing-mouth uninterrupted. If the valve is closed, the air-current is entirely cut-off from action on the wind-wheel. By adjusting this valve to occupy positions between 50 these two extremes the air-current, acting on the wheel 7, may be controlled at will. For the purpose of controlling the valve 33 a gear-

wheel 35 is made fast to one of its journals outside the casing and connected with a worm 36, formed on a shaft 37, journaled in the top 60 of the car and projecting into the interior thereof, where it is accessible to trainmen.

From the foregoing description the operation of my improved car-fan will be readily understood. As the current of air resulting 65 from the movement of the train enters the casing-mouth pointed in the direction of the train's movement the wind-wheel is rotated and motion at a reduced speed imparted to the fan-wheels through the instrumentality 70 of the gears 9 and 10, the shafts 12, the pinions 25 and 26, the horizontal shaft 27, and the pinions 29.

Having thus described my invention, what I claim is—

1. The combination with a suitable supporting structure, of a shaft journaled therein, spindles having their inner extremities journaled in said shaft, a plate made fast to the shaft, the outer portions of the spindles 80 being journaled in said plate, a gear loose on the shaft, pinions fast to the spindles and engaging said gear, a vertically-movable gravity-dog mounted on a pin engaging a socket formed in the plate, and provided with teeth 85 adapted to engage the teeth of the gear and adapted to lock the latter to turn with the shaft, and fan-blades attached to the outer extremities of said spindles.

2. The combination with a car provided 90 with an exterior casing mounted thereon, of a wind-wheel journaled in said casing, a shaft journaled in the car-frame and projecting both interiorly and exteriorly, a suitable operating connection between said shaft and 95 the wind-wheel, spindles having their inner extremities journaled in said shaft, a plate made fast to the shaft, the outer portions of the spindles being journaled in said plate, a gear loose on the shaft, pinions fast to the 100 spindles and engaging said gear, a vertically-movable gravity-dog mounted on a pin engaging a socket formed in the plate, and provided with teeth adapted to engage the teeth of the gear and adapted to lock the latter to 105 turn with the shaft, and fan-blades attached to the outer extremities of said spindles.

In testimony whereof I affix my signature in presence of two witnesses.

WILLIAM A. STEINRUCK.
